UNITED STATES PATENT OFFICE.

CLARENCE W. LANNOM, OF OAKLAND, CALIFORNIA.

HINGE.

Application filed August 3, 1925. Serial No. 47,757.

My invention relates to hinges, and it has particular reference to hinges, in which one hinge member may be so attached to one surface of a casing or other object that the pivotal center of the hinge is at a distance from the edge of said object, and in which the other hinge member is slidably attached to the surface of a panel, door, or other object, so that the latter object may be swung 10 to any desired angular position relative to the said surfaces of said objects.

It is intended by means of my invention to supply an article that is cheap, durable, simple in construction, easy to manufacture 15 and easy to attach.

By means of my invention it is also intended to produce a hinge, which permits a combined swinging and sliding movement of the attached object with a minimum effort, and which can not easily get out of 20 order.

A further object is to produce a hinge comprising a plurality of hinge members arranged on a comparatively long pintle 25 so as to preserve axial alignment of the hinge members and to assure a rigid attachment otherwise obtained only by the employment of a plurality of separate hinges, which are difficult to place in axial alignment.

Other objects and advantages will be understood from the following detail description having reference to the accompanying drawings, in which:

Figure 1 is a sectional side elevation of 35 a panel casing having one of the members of a hinge of my construction attached to a horizontal surface of the casing, and the other hinge member slidably attached to one surface of a brace panel for a table, seat, ironing board, or the like, and adapted to be swung to vertical position in the casing. The figure shows how the brace is permitted to swing over and around the edge 40 of the casing to the angle whereby it holds the table in horizontal position, the vertical positions of the table and the brace being shown in dash-and-dot lines;

Figure 2 is an enlarged fragmental view 50 of Fig. 1, illustrating more clearly the principle of my invention, and

Fig. 3 is an enlarged and broken plan 55 of the casing and the brace, with a hinge of my construction attached, the view being taken on line 3-3 of Fig. 1.

In the drawings a hinge 5, which is con-

structed according to the principle of my invention, is shown as holding in hinged relation to each other a casing 6 and a brace 7, which is pivotally connected at 8 with 60 a table 9. The hinge 5 comprises a plurality of hinge members 10 and 11, in this instance two of each, all arranged on a common pivot or pintle 12, it being understood that the number of hinge members may be 65 varied according to requirements in actual practice.

Each of the hinge members 10 and 11 is preferably made of a piece of sheet metal forming a bend *a* over the pintle 12, with 70 overlapping parts *b* and *c* of the same size and shape extending from the bend, the overlapping parts having flat faces *d* and *e* so that the members may be adapted for 75 attachment to a flat surface, although, of course, the faces *d* and *e* could be curved so as to adapt the members for attachment to a curved surface. In each of the members 10 the overlapping parts are pierced, as shown at 14, for receiving a screw or other 80 fastening element 15 therein, and in each of the members 11 the overlapping parts are pierced in such a manner as to form therein an oblong slot 16 transverse to the pintle 12 and adapted to receive a screw or other fastening element 17 slidably therein.

The drawings show a hinge of this construction, with the hinge members 10 attached to a flat, horizontal surface *f* of the casing 6, the surface *f* being in right-angled 90 relation to the outer surface *g* of the casing and forming an edge *h* where the two surfaces join each other, it being observed that the hinge members 10 are at a distance from the edge *h*. The other hinge members 11 95 are slidably attached by means of the screws 17 in the oblong slots 16 to the inner surface *i* of the panel 7, this inner surface being in right-angled relation to the end surface *j* of the panel.

It is thus seen that by this arrangement the panel 7, sliding upon the flat surfaces *d* of the hinge members 11, may be swung over and around the edge *h* to any angular position of the surfaces *i* and *f* and is thus particularly adapted to support the table 9 in horizontal position. When swung back to the vertical position, the panel is half-concealed in the casing, thus making the hinge 105 especially adapted for use on panels or doors, when it is desired to hide the hinge 110 from view and not to have the panels or

doors too conspicuously exposed when closed.

Having thus described my invention, I claim as new and wish to secure by Letters

5 Patent of the United States:

1. An article of manufacture comprising a pintle, and two pieces of sheet material forming hinge members, each having a bend over the pintle and overlapping parts of the 10 same size and shape extending therefrom, the overlapping parts of one hinge member being pierced for receiving a fastening element therein; and the second hinge member having its overlapping parts pierced 15 so as to form therein an oblong slot transverse to the pintle and adapted to receive a fastening element slidably therein; the first hinge member thus being adapted by means of the fastening element in the opening 20 to be attached to one surface and at a distance from the other surface of an object having two adjoining surfaces in angular relation to each other, and the second member by means of the fastening element in the oblong slot to be slidably attached to one surface of a second object also having 25 two surfaces in angular relation to each other, so that the second surface of the second object may be in contact with the first-mentioned surface of the first object, and the second object may slide upon the second hinge member and thus may be swung 30 over the edge of the adjoining surfaces of the first object to any desired angular position of 35 the attached surfaces of said objects.

2. An article of manufacture comprising a pintle, and two pairs of hinges formed of sheet material supported thereon so as to constitute two types of hinge members, each having a bend over the pintle and overlapping parts of the same size and shape extending therefrom, the overlapping parts of each member of one type being pierced for receiving a fastening element therein; and each member of the second type having 40 its overlapping parts pierced so as to form therein an oblong slot transverse to the pintle and adapted to receive a fastening element slidably therein; each of the first type of hinge members thus being adapted by means 45 of the fastening element in the opening to be attached to one surface and at a distance from the other surface of an object having two adjoining surfaces in angular relation to each other, and each of the second type 50 of hinge members by means of the fastening element in the oblong slot being adapted to be slidably attached to one surface of a second object also having two surfaces in angular relation to each other, so that the 55 second surface of the second object may be in contact with the first-mentioned surface of the first object, and the second object may slide upon the second type of hinge members and thus may be swung over the 60 edge of the adjoining surfaces of the first object to any desired angular position of the attached surfaces of said objects.

In testimony whereof I affix my signature,
CLARENCE W. LANNOM.
